UNITED STATES PATENT OFFICE.

CLEVELAND A. BALLOU, OF NEWTON, MASSACHUSETTS.

ASH PAN.

Application filed February 28, 1922. Serial No. 539,995.

To all whom it may concern:

Be it known that I, CLEVELAND A. BALLOU, a citizen of the United States of America, and resident of Newton, in the county of 55 Middlesex and State of Massachusetts, have invented new and useful Improvements in Ash Pans, of which the following is a specification.

My invention consists in improvements relating to ash pans and has for its object the provision of an ash receptacle by the aid of which ashes may be removed from house heating furnaces without the usual accompaniment of flying ashes which are disagreeable to the person handling the furnace and accumulate in the furnace room as dirt which is very difficult to remove. This object is attained by the use of my invention through means which prevent the deposit of 10 any ashes whatever on the floor of the ash pit below the furnace grate and which mechanically compel the deposit of ashes shaken from the grate in a receptacle which is easily removed and transported and can 15 advantageously be employed instead of the usual ash barrel for temporary storage of ashes and for the removal of the same from the house where they are accumulated.

In the drawings hereto annexed which 20 illustrate my invention,

Fig. 1 is a view in plan of an ash pan and ash catchers cooperating therewith;

Fig. 2 is a vertical cross section through the lower portion of a domestic furnace or 25 house heater and an ash pan and ash catchers such as are shown in Fig. 1;

Fig. 3 is a view in plan of an ash pan with ash catchers of a specifically different character than those shown in Fig. 1; adapted 30 to a round ash pit;

Fig. 4 is a view on an enlarged scale in cross section on line 4-4 of Fig. 3;

Fig. 5 is a view in end elevation of several 35 ash pans stacked one upon the other;

Fig. 6 is a view in perspective of an ash pan cover; and

Fig. 7 is a view in perspective of a holding bar adapted for use when ash pans are stacked as shown in Fig. 5.

House heating furnaces are of many different designs and sizes, but all of the makes with which I am acquainted have either a

rectangular or a round ash pit and in most cases the ash pit door or opening is smaller in extent horizontally measured than the 55 ash pit itself and usually smaller in width than the grate so that any ash pan capable of being inserted into the ash pit through the ash pan opening will be too small to receive the ashes falling from the 60 grate at the sides thereof, although capable of intercepting the major part of the ashes which descend from the major and middle portion of the grate.

I provide, therefore, for all cases an ash 65 pan of such width that it may be passed through the ash pit opening and of such length that it will extend from the front to the back of the ash pit below the grate and I also provide ash catchers which are disposed at either side of the ash pan in such 70 position as to intercept all ashes falling from portions of the grate which do not lie within the area of a vertical projection of the ash pan.

In either specific example of my improvements, the ash catchers or interceptors which are lateral to the main ash receptacle interfit closely with and overlap the edges of the latter, so that when the main 80 receptacle is in position in the furnace pit, this receptacle and the laterally disposed adjuncts to it collectively cover the entire area below the furnace grate, with no gaps or intervals through which ashes can pass to 85 the floor of the furnace pit.

In Figures 1 and 2 there is shown an arrangement of ash pans and catchers adapted to a rectangular ash pit. The ash pan A is substantially as long as the ash pit is deep 90 from front to back; the rear end of the ash pan may, if desired, be bowed as shown at A² and will preferably have its forward edge A³ depressed as best shown in Fig. 5. The ash pan A will also be provided with reinforcing strips A¹ which serve as runners on which the ash pan may be drawn about and also protect it against wear.

These runners also perform an important function, in that they raise the bottom of 100 the pan from the surface of the furnace pit floor, or from the floor of the cellar or basement, and thus provide a space for air circulation and heat insulation. Since the pan

A will usually be made of thin sheet metal, it is desirable, in fact practically necessary, to protect this metal itself from becoming locally overheated by the deposit of hot ash 5 or small fragments of incandescent fuel, and thus from being itself burned through. At either side of the ash pan, when the latter is placed beneath the grate G, there are fixed the inclined ash catchers B. The edges B¹ 10 of the ash catchers overlap the edges A³ of the ash pan so that ashes falling upon the catchers B must find their way into the ash pan A and not on to the floor of the ash pit P. This provision of means for effectively 15 closing all gaps through which light ash might sift through and accumulate on the furnace-pit floor has for its object not only the prevention of the light-ash nuisance but also the protection of the ash receptacle it- 20 self from accidental local overheating. If light ash is allowed to accumulate on the furnace pit floor, it will close the air circulation space between the ash-pan bottom and the furnace-pit floor (provided by 25 means of the strips or runners A') and expose the pan itself to injury by overheating. In contriving and providing all these precautionary means, the avoidance of fire-risk has been borne in mind; obviously the pres- 30ervation of the metal of which the removable ash receptacle will be composed, is an important factor in reducing fire-risk. The ash catchers B are made of sheet iron or other resilient as well as fire resistant mate- 35 rial so that the ash pan A, when inserted into the ash pit, will automatically bend the ash catchers B upward as it slides under them, finally allowing the inner edges of the ash catchers to spring downward inside the 40 edges of the ash pan as shown in Fig. 2. In the case illustrated in Figs. 1 and 2, the ash catchers B are designed to be fastened in place in the furnace and this may be done whether the ash pit be rectangular or round, 45 but in the case of the round ash pit, I believe that the form illustrated in Figures 3 and 4 will on the whole prove more convenient.

In Figs. 3 and 4 the ash pan A is of sub- 50 stantially the same character as that shown in Figs. 1 and 2 and will bear about the same dimensional relation to the ash pit. The ash catchers in this case, however, consist of segmental boxes C between which 55 the ash pan A is inserted when it is passed into the ash pit through the opening thereon. The ash pan A and segmental ash catchers C will be so proportioned that when the pan is inserted between the catchers as 60 shown in Fig. 3, these three ash intercepting factors will substantially fit and wholly occupy the round ash pit. The edges A³ of the ash pan A will then overlap the inner edges C¹ of the ash catchers C so as to prevent any ash falling from the grate from 65

being deposited on the ash pit floor. By far the larger part of the ashes shaken from the furnace grate will deposit themselves in the ash pan A. The laterally disposed ash-catchers C are provided with strips or 70 runners C³, which perform functions similar to those of the strips A'.

The ash pan with its ash catchers will preferably be placed in the ash pit to await the periodical shaking of the furnace. The 75 occasional drip of ash from the grate will in the meantime be deposited in the ash pan or be intercepted by the ash catchers. When the furnace is shaken, all the ashes, in the case shown in Fig. 1, and the major part 80 of them, in that shown in Fig. 3, will be deposited in the ash pan A and after the operation fills the pan, it is very easy, by inserting a poker or some other instrument, in the handle H (see Fig. 5) to draw the 85 pan and its contents out through the ash pit opening on to the floor of the furnace room. In the arrangement shown in Fig. 3 it will not be found necessary to remove and empty the ash catchers C so often as 90 the ash pan A, so that the ash catchers may be left in place to remain there several days before removal for emptying. The removal of these segmental ash catchers is effected through the ash pit opening by means of 95 the bails or handles C² and the contents of the ash catchers C may then be dumped into a barrel or preferably into one of the ash pans A which can with advantage be utilized instead of the ordinary ash barrel. 100

The full advantage, in respect to convenience and cleanliness of my improved ash pan arrangement, will be secured if several similar ash pans are provided. These may be somewhat tapered from top to bottom as 105 shown in Fig. 5 so that when not in use, several pans can be conveniently and compactly nested. When one of these pans filled with ashes is withdrawn from the furnace, it will be placed at one side and 110 then in conformity with the usual fire protective laws, it will be covered with a sheet metal cover such as shown in Fig. 6 and a similar ash pan will then be placed in the furnace pit. When the second ash pan is 115 full and withdrawn from the ash pit, it can be placed on top of the first one from which the cover will be removed since the second pan serves as a cover to the first. Preferably and in order to prevent the ash 120 pan from becoming spread or deformed, retaining bars such as E, Figs. 5 and 7, will be provided. Two or more such retaining bars will be laid on the bottom pan with the down-turned ends E² gripping the edges 125 A³ of the ash pan and with the up-turned clips E¹ serving as stops to hold the second ash pan in position. When a number of these ash pans have been thus filled, they can be stacked either in the furnace room or 130

taken outside and there stacked to await the rounds of the ash collector.

- In order that the presence of such an ash pan in the ash pit of the furnace may not interfere with the necessary draft, the front edge A³ of the pan is curved or depressed as shown in Fig. 3 thus to afford a sufficiently large opening for the admission of air to the bottom of the grate.
- 10 If all the ash pans are full or if for any reason it is not desired to insert an empty ash pan, it is advisable to place one of the ash pan covers beneath the grate to prevent the accumulation of ashes upon the floor of the 15 pit which will clog the air passages beneath the ash pan later inserted and possibly result in damage thereto as described above.

What I claim and desire to secure by Letters Patent is:

- 20 1. The combination, with a furnace grate, of an ash pan smaller in horizontal extent than the grate and provided with a depressed front edge, and ash catchers, disposed beneath those portions of the grate 25 which lie outside a vertical projection of the ash pan, the edges of the ash pan and ash catchers overlapping and closely interfitting, the ash pan removable independently of the ash catchers.
- 30 2. The combination with a furnace grate, of an ash pan smaller in horizontal extent than the grate, and resilient ash catchers disposed beneath those portions of the grate which lie outside a vertical projection of the 35 ash pan, the edges of the ash catchers being arranged to spring within the ash pan and closely interfit therewith as the ash pan is moved into position beneath the grate.
3. The combination with a furnace grate, 40 of an ash pan smaller in horizontal extent than the grate, and resilient ash catchers disposed beneath those portions of the grate which lie outside a vertical projection of the ash pan, the edges of the ash catchers being arranged to spring within the ash pan and closely interfit therewith as the ash pan is moved into position beneath the grate.
- 45 4. The combination with a furnace grate, of an ash pan smaller in horizontal extent than the grate, and provided with a depressed front edge, ash catchers disposed beneath those portions of the grate which 50 lie outside a vertical projection of the ash pan, the edges of the ash pan and ash catchers overlapping and closely interfitting, and reinforcing strips on said ash pan providing an air space therebeneath and serving as runners therefor in removing and inserting said ash pan.
5. The combination with a furnace grate, 55 of an ash pan smaller in horizontal extent than the grate, and ash catchers disposed beneath those portions of the grate which lie

outside, a vertical projection of the ash pan, the edges of the ash pan and ash catchers overlapping and closely interfitting, the front edge of the ash pan being depressed to provide the necessary draft to the grate. 70

6. The combination with a furnace grate, of an ash pan smaller in horizontal extent than the grate, and ash catchers disposed beneath those portions of the grate which lie outside a vertical projection of the ash 75 pan, the edges of the ash pan and ash catchers overlapping and closely interfitting, the front edge of the ash pan being depressed to provide the necessary draft to the grate, and reinforcing means on said ash pan providing an air space thereunder and serving as runners in its removal and insertion beneath the grate. 80

7. Ash receiving apparatus adapted to be installed in the ash pit of a furnace comprising an ash pan of a size to pass through the door of the pit and ash catchers arranged to be secured beneath the furnace grate under those portions of the grate which lie outside a vertical projection of the ash pan, 90 the edges of the ash pan and ash catchers overlapping and closely interfitting, the ash pan being removable independently of the ash catchers.

8. Ash receiving apparatus adapted to be 95 installed in the ash pit of a furnace comprising an ash pan of a size to pass through the door of the pit and resilient ash catchers arranged to be secured within the pit under those portions of the grate which lie outside 100 a vertical projection of the ash pan, the edges of the ash catchers being arranged to spring within the ash pan and closely interfit therewith as the ash pan is moved into position beneath the grate. 105

9. Ash receiving apparatus adapted to be installed in the ash pit of a furnace comprising an ash pan smaller in horizontal extent than the grate to permit it to pass through the ash pit door and ash catchers arranged 110 to be secured within the pit under those portions of the grate which lie outside a vertical projection of the ash pan, the edges of the ash pan and ash catchers overlapping and closely interfitting, the front edge of 115 the ash pan being depressed to provide the necessary draft to the grate.

10. Ash receiving apparatus adapted to be installed in the ash pit of a furnace comprising an ash pan smaller in horizontal extent 120 than the grate to permit it to pass through the ash pit door, resilient ash catchers arranged to be secured within the pit under those portions of the grate which lie outside a vertical projection of the ash pan, the edges of the ash pan and ash catchers overlapping and closely interfitting, the front edge of 125 the ash pan being depressed to provide the necessary draft to the grate, and reinforcing strips on said ash pan providing 130

an air space therebeneath and serving as runners therefor in removing and inserting said ash pan.

11. Ash receiving apparatus for use in the ash pits of furnaces in conjunction with inwardly disposed and downwardly inclined resilient ash catchers comprising an ash pan of a size to pass through the ash pit door having sides arranged to be in overlapped and closely interfitting engagement with the 20 ash catchers, the front edge of the pan being depressed to provide the necessary draft to the grate, and reinforcing means on the ash pan providing an air space thereunder and serving as runners in its removal and insertion beneath the grate.

12. Ash receiving apparatus for use in the ash pits of furnaces in conjunction with

inwardly disposed and downwardly inclined resilient ash catchers comprising an ash pan of a size to pass through the ash pit door having sides arranged to be in overlapped and closely interfitting engagement with the 20 ash catchers, the front edge of the pan being depressed to provide the necessary draft to the grate, and reinforcing means on the ash pan providing an air space thereunder and serving as runners in its removal and insertion beneath the grate.

Signed by me at Boston, Massachusetts, this twenty-fifth day of February, 1922.

CLEVELAND A. BALLOU.
